UNITED STATES PATENT OFFICE.

HENRY J. HAIGHT, OF NEW YORK, N. Y.

MOVABLE LAMP-CONE.

SPECIFICATION forming part of Letters Patent No. 247,821, dated October 4, 1881.

Application filed May 8, 1879.

To all whom it may concern:

Be it known that I, HENRY J. HAIGHT, of the city, county, and State of New York, claim to be the sole and original inventor of a Machine for Regulating the Igneous Heat in Poultry-Hatching Machines, which I denominate "Haight's Movable Lamp-Cone," the material and construction being set forth and described, reference being had to the drawings herewith sent, in the following specification.

Figure 1 is a perspective elevation with parts broken out, and Fig. 2 is a plan view, of my construction.

My invention consists of certain improvements in the lamp-cone used in my rotary incubator, patented December 26, 1871, which are as follows:

The rod R, Fig. 1, entering the lamp-vessel L by the way of a perforation made in the vessel, is twisted in the first crank, *a*, and proceeds up to the second crank, *b*, which is turned over the peg P, jutting from the lamp-cone C. It continues its course down to the third crank, *c*, and horizontally to the fourth crank, *d*, and up again to the fifth crank, *e*, which turns over the peg P' on the other side of the cone, runs down to the sixth crank, *f*, and finally goes out of the vessel. By the rod outside the ves-

sel being turned downward and upward, the cranks inside, by means of the pegs, together with the cone to which they are attached, perform the same work on the cone, and for the purpose as described in my patented rotary incubator.

Affixed to the wick-tubing W is a support, S, upon which the cone rests when lowered.

I am aware that a lamp-extinguishing device has heretofore been constructed whereby the flame-extinguishing tube is raised by means of a bent rod turning on its axis and a connecting-link between the said rod and tube. My invention, besides being different in construction from such a device, is for an entirely different purpose—namely, for automatically regulating the height of a cone or tube around the burner, acting as a deflector and heat-regulator.

I claim as my invention—

The combination of the rod R, twisted in cranks *a b c d e f*, and the pegs of the lamp-cone P P', substantially as described.

HENRY J. HAIGHT.
